UNITED STATES PATENT OFFICE.

EDWARD S. STIMPSON, OF HOPEDALE, MASSACHUSETTS, ASSIGNOR TO DRAPER COMPANY, OF HOPEDALE, MASSACHUSETTS, A CORPORATION OF MAINE.

FILLING-REPLENISHING LOOM.

1,123,148.

Specification of Letters Patent.

Patented Dec. 29, 1914.

Application filed June 11, 1914. Serial No. 844,549.

To all whom it may concern:

Be it known that I, EDWARD S. STIMPSON, a citizen of the United States, residing at Hopedale, county of Worcester, State of Massachusetts, have invented an Improvement in Filling-Replenishing Looms, of which the following description, in connection with the accompanying drawing, is a specification, like characters on the drawing

10 representing like parts.

This invention relates to a means for preventing the operation of the filling replenishing mechanism in an automatic loom upon the failure of the filling feeder properly to position a filling carrier or transerrer after the indication of entire or partial exhaustion in the running shuttle, and the object is to provide a simple and efficient means for securing this result, particularly 20 by or through the restraining of the operation of a horizontally movable shuttle feeler when the filling feeder is improperly positioned, and also particularly by or through the agency of the detent pawl controlling the 25 rotation and position of the feeder.

The nature of the invention will appear more fully from the accompanying description and drawings and will be particularly pointed out in the claims.

30 The drawings show so much of an ordinary automatic filling replenishing loom together with the parts constituting a preferred form of this invention as is necessary to an understanding of the invention.

35 In the drawings, Figure 1 is an end elevation and partial transverse section of a sufficient portion of an automatic filling replenishing loom of the "Northrop" type with the parts involved in this invention applied thereto; Fig. 2 is a view partially in vertical cross section through the hopper or feeder showing parts concerned in the present invention; Fig. 3 is a plan view partially in horizontal cross-section of the additional 40 parts required to apply a preferred form of this invention to this type of loom.

The construction of the loom illustrated and to which a preferred form of the invention is shown as applied is of the well known "Northrop" type, such for example as is illustrated and described in the patent to Stimpson No. 664,790 granted December 25, 1900, and in connection therewith is shown a horizontally movable shuttle feeler 50 and thread cutter mechanism such as is illus-

trated and described in detail in the patent to Davis No. 1,091,813 granted March 31, 1914, and in view of the complete description and illustration of the mechanism of the loom and shuttle feeler contained in these 60 two patents it will be unnecessary here to describe in detail anything more than those parts directly concerned with the present invention.

The breast beam of the loom 1 has fixedly 65 mounted thereon the usual filling feeder which comprises two disks or plates 2 to receive, hold and position the spare filling carriers 3. The hopper stand 4 with its integral casing 5 inclosing the disk 2 is secured 70 in the usual manner to the breast beam. The filling carriers or bobbins 3 are as usual held by their butts and tips by and between the two disks of the hopper or feeder in a circularly arranged series, the seats 6 for 75 the butts being shown in Fig. 2. The filling carriers are brought one by one into position for transfer from the hopper or feeder to the running shuttle by suitable mechanism, such for example as that disclosed in the 80 aforesaid patent to Stimpson No. 664,790. This mechanism includes a toothed disk or ratchet wheel 7 rotatable with and located at the inner side of the disk 2 and having its teeth corresponding in number to the holding 85 devices for the filling carriers, a dog 8 pivoted at 9 on the transerrer 10 and co-operating with the ratchet wheel 7, and a detent pawl 11 engaged between the teeth of the ratchet wheel 7. It will thus be seen 90 that in the manner described in the Stimpson Patent No. 664,790 upon movement of the transerrer 10 the feeder is rotated step by step to bring a filling carrier into position for transfer, and when the filling carrier is 95 in proper position for transfer the detent pawl 11 will be seated in one of the notches of the ratchet wheel 7. This detent pawl is pivoted at 12 to the hopper stand, and its weighted foot 13 serves to hold it in engagement 100 with the ratchet wheel.

The filling replenishing mechanism comprises the transerrer 10, already referred to, pivotally mounted at 14 on the hopper stand and operating when depressed or 105 moved downwardly to transfer a filling carrier from the hopper or feeder to the shuttle. A transerrer operating dog 15 as in the construction illustrated in the aforesaid patent to Davis No. 1,091,813 is pivoted at 16 to 110

2
the depending arm 17 of the transferrer and moves in a horizontal direction guided by the hopper stand. A bunter 18 is pivotally mounted at 19 to the lay 20 to coöperate with the transferrer dog.

5 The shuttle feeler mechanism is carried by the bracket 21 mounted on the hub 22 of the transferrer and held in place by the set screw 23. This bracket carries the upwardly projecting arm 24 and a horizontally and forwardly projecting arm terminating in the bearing socket 25 in which is secured by set screws 26 a guide bar 27 projecting rearwardly toward the lay. The shuttle feeler 28 is supported from a sleeve 29 mounted to slide rectilinearly and rotate slightly on the guide bar 27, and movement is given to the sleeve 29 by a bell crank lever fulcrumed at 30 on the arm 24 of the bracket 10 21, the longer arm 31 of the bell crank lever being pivotally connected at 32 to an arm projecting from the sleeve 29, while the shorter arm 33 of the bell crank lever is provided with a pin 34 engaging the slotted end 15 25 of a link 35 pivoted at its lower end at 36 to the usual arm 37 extending rearwardly from the usual controlling rock shaft 38, and held downwardly by the spring 39. In this form 20 30 of mechanism as more fully explained in the aforesaid patents when a replenishment of filling is called for the shuttle feeler supporting sleeve 29 is moved rearwardly rectilinearly on the guide bar 27 until it is stopped by the pin 40 at the rearward end of 35 40 the guide bar. If the shuttle is properly boxed when the lay beats up a trip 41 carried with the bunter 18 striking a depending heel 42 on the shuttle feeler support will throw the bunter 18 into position so 45 50 that it will strike the nose of the dog 15 and thus operate the transferrer 10 to effect the filling replenishment. If, however, the shuttle is improperly boxed the rearward movement of the shuttle feeler will be restrained by contact with the shuttle, the trip 41 will not reach the heel 42, the bunter 18 will accordingly not be swung into position to strike the dog 15, and the shuttle feeler and its support will be pushed forwardly by 55 60 the shuttle on the guide bar 27 and there will be no actuation of the transferrer.

The present invention is concerned as already stated with means to prevent the transfer of the filling carrier taking place when the filling carrier is improperly positioned by the feeder or hopper for transfer. As fully explained in the patent to F. G. and J. H. Cobb No. 780,266 granted January 7, 1905, should the hopper or feeder fail 65 70 properly to present a filling carrier in accurate position for transfer the transferrer upon the next operation of the replenishing mechanism would improperly engage the filling carrier and injure it or some of the adjacent mechanism. This undesirable re-

sult is prevented by the present invention and this is done by restraining the movement of the horizontally movable shuttle feeler when the filling carrier is so improperly positioned.

70 In the construction illustrated a bracket 43 is secured as by a set screw 44 to the front of the hopper stand 4, and this bracket has forwardly projecting arms 45 provided with horizontally alined bearings in which is mounted a shaft 46. A helical spring 47 surrounds the shaft and is secured at one of its ends to one of the arms 45 and at the other of its ends to a collar 48 adjustably secured to the shaft 46. A catch 49 is 75 clamped to the inner end of the shaft 46 and provided with a hooked rearward end. The parts are so arranged and adjusted that the spring 47 normally acts to maintain the catch 49 elevated with its hooked end out of 80 the path of the shuttle feeler supporting sleeve 29 while if the shaft 46 be rocked to move the catch 49 downwardly it will be brought into the path of the said sleeve and restrain the movement of the shuttle 85 feeler, preventing the operation of the trans- 90 ferrer just as would be done if the move- 95 ment of the shuttle feeler were restrained by an improperly boxed shuttle. The other end of the shaft 46 is provided with a de- 100 pending finger 50. A slide bar 51 rests upon the hub of the transferrer and is pivotally secured at 52 to the detent pawl 11. If now a filling carrier be brought into proper posi- 105 tion for transfer the detent pawl 11 will be firmly seated in a notch in the ratchet wheel 7 and the slide bar 51 will not move the 110 depending finger 50; if however, the filling 115 feeder fails to move to a position properly to position a filling carrier for transfer then the detent pawl 11 will not be seated firmly in a notch in the ratchet wheel 7, but will be left in a more or less forward position, and consequently, the slide bar 51 will be moved forwardly rocking the shaft 46 and depress- 120 ing the catch 49 into the path of the shuttle 125 feeler support 29. Thus, it will be seen that this will prevent transfer taking place, and thus the object of the invention will be secured.

The invention thus presents a means ren- 130 dered active by the hopper or feeder when improperly positioned for the transfer of a filling carrier to restrain the movement of the horizontal shuttle feeler, and thus to prevent the operation of the transferrer.

Having fully described my invention, what I claim as new and desire to secure by Letters Patent is:

1. In a loom, automatic filling replenishing mechanism including an intermittently movable feeder to contain a plurality of filling carriers, a transferrer to transfer a filling carrier therefrom, a shuttle feeler, and means to prevent the operation of the trans- 135

ferrer when the movement of the shuttle 5
feeler is restrained, a movable catch nor-
mally held out of the path of the shuttle
feeler and moved by the feeder into the path
5 of the shuttle feeler when the feeler is im-
properly positioned for transfer of a filling
carrier whereby when the feeder is improp-
erly positioned for transfer the movement of
the shuttle feeler will be restrained to pre-
10 vent the operation of the transferrer.

2. In a loom, automatic filling replenish-
ing mechanism including an intermittently
movable feeder to contain a plurality of fill-
ing carriers, a ratchet wheel movable with
15 said feeder and provided with teeth corre-
sponding to the filling carriers, a detent
pawl engaging and seated between said teeth
when the feeder is properly positioned for
transfer of a filling carrier, a transferrer to
20 transfer a filling carrier from the feeder, a
shuttle feeler, means to prevent the oper-
ation of the transferrer when the movement
of the shuttle feeler is restrained, and means
rendered active by the said detent pawl
25 when not properly seated between the teeth
of the ratchet wheel to restrain the move-
ment of the shuttle feeler and thus to pre-
vent the operation of the transferrer.

3. In a loom, automatic filling replenish-
ing mechanism including an intermittently
movable feeder to contain a plurality of fill-
ing carriers, a ratchet wheel movable with
35 said feeder and provided with teeth corre-
sponding to the filling carriers, a detent
pawl engaging and seated between said teeth
when the feeder is properly positioned for
transfer of a filling carrier, and means con-
40 trolled by said detent pawl to prevent the
transfer of a filling carrier from the feeder
when the detent pawl is not properly seated
in the ratchet wheel and consequently the
filling carrier is properly positioned for
45 transfer.

4. In a loom, automatic filling replenish-
ing mechanism including an intermittently
movable feeder to contain a plurality of fill-
ing carriers, a transferrer to transfer a filling
carrier therefrom, a horizontally move-
50 able shuttle feeler and means to prevent the
operation of the transferrer when the hori-
zontal movement of the shuttle feeler is re-
strained, and means rendered active by the
feeder when improperly positioned for the

transfer of a filling carrier to restrain the
horizontal movement of the shuttle feeler 55
and thus to prevent the operation of the
transferrer.

5. In a loom, automatic filling replenish-
ing mechanism including an intermittently
movable feeder to contain a plurality of fill- 60
ing carriers, a transferrer to transfer a fill-
ing carrier therefrom, a shuttle feeler, and
means to prevent the operation of the trans-
ferrer when the movement of a shuttle feeler
is restrained, a ratchet wheel movable with 65
the feeder and provided with teeth corre-
sponding to the filling carriers, a detent
pawl engaged and seating between said teeth
when the feeder is in proper position for
transfer of a filling carrier, a movable catch 70
normally held out of the path of the shuttle
feeler, a slide bar connected to the detent
pawl and acting when the detent pawl is
improperly seated to move the said catch
into the path of the shuttle feeler thus to 75
restrain the movement of the shuttle feeler
and prevent the operation of the transferrer.

6. In a loom, automatic filling replenish-
ing mechanism including an intermittently
movable feeder to contain a plurality of fill- 80
ing carriers, a transferrer to transfer a fill-
ing carrier therefrom, a shuttle feeler, and
means to prevent the operation of the trans-
ferrer when the movement of a shuttle feeler
is restrained, a ratchet wheel movable with 85
the feeder and provided with teeth corre-
sponding to the filling carriers, a detent
pawl engaged and seating between said teeth
when the feeder is in proper position for
transfer of a filling carrier, a catch movable 90
into the path of the shuttle feeler, a spring
normally acting to hold the catch out of the
path of the shuttle feeler, a slide bar con-
nected to the detent pawl and acting when
the detent pawl is improperly seated to move 95
the said catch into the path of the shuttle
feeler thus to restrain the movement of the
shuttle feeler and prevent the operation of
the transferrer.

In testimony whereof, I have signed my 100
name to this specification, in the presence of
two subscribing witnesses.

EDWARD S. STIMPSON.

Witnesses:

HARRY L. WILBUR,
DANA OSGOOD.

It is hereby certified that in Letters Patent No. 1,123,148, granted December 29, 1914, upon the application of Edward S. Stimpson, of Hopedale, Massachusetts, for an improvement in "Filling-Replenishing Looms," an error appears in the printed specification requiring correction as follows: Page 3, line 5, second occurrence, for the word "feeler" read *feeder*; and that the said Letters Patent should be read with this correction therein that the same may conform to the record of the case in the Patent Office.

Signed and sealed this 19th day of January, A. D., 1915.

[SEAL.]

R. F. WHITEHEAD,

Acting Commissioner of Patents.
